UNITED STATES PATENT OFFICE

2,546,707

BAFFLE TYPE EXHAUST SILENCER

John Wallingford, Perkins Mills, Quebec, Canada

Application July 5, 1947, Serial No. 759,137

4 Claims. (Cl. 181—51)

1

This invention relates to improvements in an exhaust silencer for internal combustion engines and appertains particularly to one in which a supplementary stream of fluid is blended with the motor's exhaust.

An object of the invention is to provide a silencing device wherein the motor output of substantially spaced or intermittent exhaust impulses are united with an added fluid stream as in a spiralling column to produce a continuous, even and uninterrupted flow.

A further object of the invention is to provide an exhaust silencer without setting up back pressure by combining a flow of fluid with the motor's exhaust in such manner as to produce a smooth, steady and as-nearly-as-possible vibrationless stream.

A still further object of the invention is the provision of a silencing apparatus for the exhaust of internal combustion engines of the nature described that is characterized by structural simplicity; operating efficiency and reasonable cost of production whereby the same is rendered commercially desirable.

To the accomplishment of these and related objects as shall become apparent as the description proceeds, the invention resides in the construction, combination and arrangement of parts as shall be hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings:

Figure 1 is a vertical sectional elevation of a possible embodiment of the invention;

Figure 2 is a sectional elevation of a modified form of input for the silencer; and

Figure 3 is a sectional detail of the simplified outlet end of this modified form.

In this exhaust silencer the main jacket or housing 5 is shown in thread-coupled halves merely for the purpose of facilitating assembly. At the input end 6, that shall be designated the "upper" end for convenient reference, the exhaust manifold tube 7 enters, continuing into the housing 5 and bending so that its mouth 8 is aligned with the housing axis. Here it lies within a concentric sleeve 9, having approximately twice the cross-sectional area of the tube 7, and provided with spiralling fins 10.

Beyond the delivery end of the sleeve 9 a

series of staggered baffles 11 extend in from opposite sides of the housing 5 and in the lower end of the said housing, where it may be partially shielded by a final and perforated baffle plate 12, the outlet 14 occurs.

A well or pocket 15 is provided in this lower or outlet end of the housing and from an opening 16 therein, protected by a screen or filter 17, a duct 18 leads to a motor driving pump unit 19 that feeds, as by the pipe 20, through a secondary inlet 21 in the upper or inlet end of the housing 5, to the spiralling or vortex sleeve 9.

In use, a body of suitable fluid, in either gaseous or liquid state, capable of relatively easy and rapid separation from the exhaust is driven by the pump 19 in a fast flowing stream through the finned sleeve 9 where it is spun into a vortex as it sucks in the exhaust entering through the mouth 8, smoothing out the spaced exhaust impulses into an even continuous spinning current.

Billowing against the baffles 11, the spinning is disturbed and interrupted and the exhaust gases and heavier stable driving fluid are completely separated so that on reaching the lower or outlet end of the housing, the former emerges in a quiet, gentle stream from the upper outlet 14 while the latter collecting in the well 15 is drawn back by the circulating pump 19 to the circuit line 20. Depending on the size or rating of the engine whose exhaust is being received, with respect to the flow of the motor driven fluid, the mouth 8 of the exhaust tube 7 may be restricted as at 22 to provide a venturi.

In the modification shown in Figure 2, an air inlet cone 25 feeds through the secondary inlet 21' in the upper end 6' of the housing 5' to the finned or vortex sleeve 9 in the same way as the motor driven fluid did in the pipe 20, just described. This type depends on a draft of air of sufficient velocity being fed through the cone 25 as by the movement of the vehicle or craft in which the motor is mounted. A simplified form of delivery end, as shown in Figure 3, is allowed where this is done; a single outlet 26 sufficing.

From the foregoing description taken in connection with the accompanying drawings, it will be manifest that an exhaust silencer for internal combustion engines is provided that will fulfill all the necessary requirements of such a device, but as many changes could be made in the above description and many apparently widely different embodiments of the invention may be constructed within the scope of the appended claims, without departing from the spirit or scope there-

of, it is intended that all matters contained in the said accompanying specification and drawings shall be interpreted as illustrative and not in a limitative or restrictive sense.

Having thus described the invention, what I claim as new and desire to secure by Letters Patent is:

1. A silencing apparatus for the exhaust of internal combustion engines comprising in combination with the engine's exhaust pipe, a concentric vortex-producing declining tube surrounding the outlet of said exhaust pipe, a stream of fluid driven through said tube and combining with the engine's exhaust therein, said vortex-producing tube beginning in advance of and continuing far beyond the end of said exhaust pipe and having approximately twice the cross-sectional area of said pipe, stream-buffeting, separating baffles beyond said tube and separate outlets for the exhaust gases and the driven fluid respectively the former being at the top of the lower end of the silencer and the fluid outlet issuing from a well in the bottom.

2. A silencer for the exhaust of internal combustion engines comprising a main elongated housing, the open delivering end of the engine exhaust pipe extended a short distance into one end of said housing and terminating coaxial therewith, a concentric sleeve surrounding said exhaust pipe and extending substantially beyond the open end of said pipe, vortex-inducing fins

5 on the inside of said sleeve beginning just in advance of and continuing well beyond the open delivering end of said exhaust pipe, outlets near the top and bottom respectively of the opposite end of said housing, a return conduit connecting the lower of said outlets with said sleeve and a secondary stream of fluid circulated therein.

10 3. The combination with the structure set forth in claim 2 wherein said exhaust pipe and said sleeve each enter said housing in angular relation.

15 4. The combination with the structure set forth in claim 2 of flow-deflecting baffles in staggered position on the inside of said housing between the end of said sleeve and said outlets, said baffles being inclined angularly in the direction of flow through said housing and each deflecting toward its successor.

JOHN WALLINGFORD.
